UNITED STATES PATENT OFFICE.

BERTIE LEE ENOCHS, OF SPRINGFIELD, ILLINOIS, ASSIGNOR OF FORTY-FIVE PER CENT TO ALVIN E. CORMENY, OF SPRINGFIELD, ILLINOIS.

CIRCUIT MAKER AND BREAKER.

Application filed April 15, 1924. Serial No. 706,739.

To all whom it may concern:

Be it known that I, BERTIE L. ENOCHS, a citizen of the United States, residing at Springfield, in the county of Sangamon and State of Illinois, have invented certain new and useful Improvements in Circuit Makers and Breakers, of which the following is a specification, reference being had therein to the accompanying drawing.

My invention relates to new and useful improvements in means for making and breaking a circuit and more particularly to means for automatically turning on or shutting off the current in a trolley line which extends into a mine or similar place, the principal object of the invention residing in the provision of means whereby the movement of a locomotive will automatically turn on the current as it passes into the mine and will automatically turn off the current upon leaving the mine.

A further object of the invention resides in the provision of means for energizing a magnet which attracts a switch blade for closing the circuit and energizing a solenoid or the like for operating the switch blade to break the circuit, the switch blade being mounted in a novel manner so as to be readily operated in either direction and a resistance unit being used for reducing the voltage which is admitted to the magnet and solenoid from the trolley line.

Still another object consists in providing the locomotive with a contact member which will engage a contact in the trolley line for opening or closing the circuit, the contact member on the locomotive engaging one side of the contact on the trolley as the locomotive passes into the mine and the opposite side of the contact on the trolley as the locomotive passes out of the mine.

With the above and other objects in view, which will appear as the description proceeds, my invention consists in the novel details of construction and arrangement of parts described in the following specification and illustrated in the accompanying drawings, and while I have illustrated and described the preferred embodiments of the invention as they now appear to me it will be understood that such changes may be made as will fall within the scope of the appended claims.

In the drawings:

Fig. 1 is a front elevation.

Fig. 2 is a side elevation.

Fig. 3 is a top plan.

Fig. 4 is a front elevation showing my circuit maker and breaker in combination with a mine trolley line with a mine locomotive shown in side elevation.

Fig. 5 is an end view of the contact plates carried by the trolley wire, and

Fig. 6 is a top plan of the trolley wire contact plates.

At the present day in a great many mines electric locomotives are used for haulage purposes and receive their current from a trolley line or wire which extends into the mine. For a number of reasons it is desirable that when the electric locomotive is not in use that the current be cut off from the trolley wire or certain sections thereof and for this reason I have provided novel means whereby the current is automatically turned on in the trolley line or wire or a section thereof, as the locomotive passes into the mine and is automatically cut off as the locomotive passes from the mine.

In the drawing 1 indicates an electric locomotive having the usual form of trolley pole 2 with a wheel 3 on its upper end and 4 represents a contact member secured adjacent the trolley wheel and preferably extending horizontally from the side thereof. Sections of a trolley line or wire are indicated at 5 and 6 and their ends are connected by an insulated joint or block 7. Supported on or adjacent to the section 5 of the trolley wire is a contact member indicated generally at 8 this member having the side bars or plates 9 and 10 which are elongated as shown and extend on opposite sides of the wire.

Supported adjacent the trolley, and preferably at the point where the ends of the sections of the wire are connected is a base or supporting plate 11 which carries the elements of the switch which connect the sections of the trolley wire and either make or break the circuit through said wire. Secured to the support 11 are the terminals 12 and 13, a wire 14 being connected to the terminal 12 and leading to the section 5 of the trolley wire and a wire 15 being connected to the terminal 13 and leading to the section 6 of the trolley wire. Adjustably connected to the terminals 12 and 13 respectively are the bars 16 and 17 having the spaced arms 18 and 19 respectively to receive the arms of a

switch blade in a manner to be later described.

Secured to the support 11 is a bracket 20 to which is pivotally connected the switch arm 21, the upper end of which is bifurcated as shown at 22 and the lower end of which is bifurcated to form the parallel arms 23. Secured to or formed on the upper bifurcated end 22 is a transversely extending bar 24 which carries the switch blades or arms 25. Secured to the arms 23, preferably adjacent the lower ends thereof, is a transversely extending bar 26 which in turn has connected thereto the rod 27 which is secured to the core 28 of the solenoid 29, the solenoid being secured to the support 11. The switch arm 21 has secured thereto or formed thereon, intermediate ends thereof, a transversely extending bar 30 which is adapted to be attracted by the horseshoe magnet 31, said magnet being connected to the support 11. A resistance unit 32 and a junction block 33 are also secured to the support 11. A coiled spring 34 is secured at one end to the support 11 and at the opposite end to one of the arms 23, this coiled spring normally drawing the lower end of the switch arm towards the solenoid and holding the contact blades 25 away from the arms 18 and 19 so that the circuit will be broken. Coiled springs 35 are secured to the support 11 in position to be engaged by the ends of the bar 26, as shown, said coiled springs 35 acting as bumpers.

A lead wire 36 extends to the junction block 33 and a wire 37 leads from said junction block to the horseshoe magnet 31. A lead wire 38 leads to the junction box 33 and extending from said junction block and lead wire is a wire 39 which leads to the solenoid 29. A wire 40 leads from the resistance unit 32 through the junction block 33 to the negative wire 41.

Having now fully described the details of construction I will now endeavor to more clearly bring out the operation. While I have only shown two sections of trolley wire I wish it understood that any number of sections might be used with associated parts so that when desired the current between adjacent sections may be turned on or turned off automatically by the movement of the electric locomotive. Assuming that the parts or elements are in the positions illustrated in the drawing and that the locomotive is passing into the mine, the current will be on in the section 5 but off in the section 6. As the locomotive reaches the proper position the trolley contact 4 will engage the plate 9 and cause the current to pass through the horseshoe magnet 31 and attract the bar 30 of the switch arm 21. The switch arm will swing upon the bracket 20 and cause the switch blades 25 to engage the arms 18 and 19 carried by the terminals 12 and 13. This

will close the circuit and allow the current to pass into the section 6 of the trolley wire so that the locomotive may pass on into the mine. As the locomotive passes out from the mine the trolley contact 4 will engage the plate 10 of the trolley contact member 8 and cause the current to pass through the wire 39 to the solenoid 29, this attracting the core 28 of the solenoid and drawing the lower end of the switch arm 21 towards the solenoid so as to remove the switch blades 25 from engagement with the contacts 18 and 19. This movement of the contact arm will break the circuit between the trolley wire sections 5 and 6 and shut off the current from the section 6. The resistance unit 32 will reduce the current passing between the horseshoe magnet and solenoid.

Having fully described my invention what I claim as new and desire to secure by Letters Patent is:

1. In combination with a plurality of trolley sections and a locomotive, a circuit maker and breaker, said circuit maker and breaker comprising terminals connected to the sections of the trolley, a switch arm, means operable by the movement of the locomotive in one direction to attract one end of the switch arm to close a circuit between the trolley sections, and means operable by the movement of the locomotive in the opposite direction to attract the opposite end of the switch arm to open the circuit between the trolley sections.

2. In combination with a plurality of trolley sections and a locomotive, a circuit maker and breaker, said circuit maker and breaker comprising terminals connected to the sections of the trolley, a switch arm, means operable by the movement of the locomotive in one direction to attract one end of the switch arm to close a circuit between the trolley sections, and separate means operable by the movement of the locomotive in the opposite direction to attract the opposite end of the switch arm to open the circuit between the trolley sections.

3. In combination with a plurality of trolley sections and a locomotive, a circuit maker and breaker, said circuit maker and breaker comprising terminals connected to the sections of the trolley, a switch arm, a magnet, a solenoid, means for energizing the magnet upon movement of the locomotive in one direction to attract one end of the switch arm to close a circuit between the trolley sections and means for energizing the solenoid upon movement of the locomotive in the opposite direction for attracting the opposite end of the switch arm to open the circuit between the trolley sections.

In testimony whereof I hereunto affix my signature.

BERTIE LEE ENOCHS.
